UNITED STATES PATENT OFFICE.

PETER PATTERSON, OF MCKEESPORT, PENNSYLVANIA, ASSIGNOR TO
NATIONAL TUBE COMPANY, OF NEW YORK, N. Y., A CORPORATION
OF NEW JERSEY.

SEAMLESS-TUBE-DRAWING MECHANISM.

SPECIFICATION forming part of Letters Patent No. 741,369, dated October 13, 1903.

Application filed June 28, 1901. Serial No. 66,369. (No model.)

To all whom it may concern:

Be it known that I, PETER PATTERSON, a resident of McKeesport, in the county of Allegheny and State of Pennsylvania, have invented a new and useful Improvement in Seamless-Tube-Drawing Mechanism; and I do hereby declare the following to be a full, and exact description thereof.

My invention relates to mechanism for drawing tubes from cup-shaped blanks, and more particularly to mechanism for drawing large and heavy tubes from cup-shaped blanks in which the mandrel or punch is pivoted to the pushing mechanism, so as to be capable of being swung to one side to receive the cup-shaped blank.

One of the objects of my invention is to provide suitable mechanism for so swinging the punch or mandrel to one side to receive the blank and then swinging the same back into line with the dies.

A further object of my invention is to so construct the frame for holding a series of dies that it can be more accurately, quickly, and cheaply made than the usual frames for holding a series of dies.

In the manufacture of seamless metal tubing one method consists in forcing a planchet or cup-shaped blank through a die or series of dies by means of a reciprocating mandrel or punch, the operation being repeated through dies of decreasing diameter or through a series of dies of gradually-decreasing diameter until the cup-shaped blank has been drawn down to the desired thinness of walls and length of tube. It is customary in horizontal draw-benches of this type to hinge the mandrel or punch to the pushing mechanism, so that it can be swung to one side to receive the cup-shaped blank, it being swung sidewise by hand. This method of drawing seamless tubing necessitates powerful mechanism, and the mandrel or punch is necessarily very heavy, so that considerable difficulty has been experienced in swinging it outwardly to receive the blank and back again into line with the dies. As a consequence the size and weight of the mandrel have been limited, thereby limiting the size, weight, and length of the tubing to be drawn, it hav-

ing been impracticable in former apparatus to swing a mandrel-bar of sufficient size to draw very large and heavy tubing. Furthermore, if the cup-shaped blank is heated, as it must be for making most forms of heavy and large tubes, it is essential that it be gotten onto the mandrel and into the dies as quickly as possible, so as not to lose the heat. The quicker this is done the greater will be the reduction of the blank or cup in the dies. With the old hand appliances it is difficult to swing the mandrel or punch back into line with the dies with sufficient rapidity to prevent loss of heat in the blank, so that the greatest possible reduction of the same on the dies is not secured. The time necessary to swing the mandrel or punch back into line with the dies by the old hand appliances is liable to vary considerably with different blanks, so that uniformity of output is not obtained.

One of the objects of my invention is to overcome these difficulties and to provide apparatus whereby very large and heavy tubes can be drawn from cup-shaped blanks with ease, rapidity, and uniformity. To this end it comprised, generally stated, in combination with a drawing-press having a mandrel or punch hinged to the reciprocating mechanism, of mechanism whereby the mandrel or punch can be swung to one side to receive the cup-shaped blank and then swung back quickly into line with the dies in position for the reciprocating mechanism to force the mandrel or punch and blank through the dies.

In drawing tubing by the above-described method from blanks which are heated prior to drawing it is desirable that the blank be forced through a series of dies of gradually-decreasing diameter at a single reciprocation of the mandrel or punch, so that the said blank may be given a number of reductions and brought down to the desired gage at a single heat. It has therefore been the practice to use a die-holding frame having a series of seats for receiving one or more dies, as desired, the common practice being to form said frame as a single casting provided with a series of seats. As these seats must be formed accurately, it is necessary to machine the same; but by reason of forming the seats

in a single block or casting considerable difficulty has been experienced in doing this. Special tools or machinery are required, and even then the process is slow, tedious, and 5 very expensive.

Another object of my invention is to reduce the expense of constructing such die-holding frames and to provide a frame for holding a series of dies which can be more 10 accurately and cheaply made than the old form of frame.

To this end it consists in making such frame of a series of blocks or plates, each of which is provided with parallel flat faces, one 15 of which serves as a seat for the die or die-holder, so that said seat can be readily machined on an ordinary planer, suitable means being provided for securing said series of blocks together to form a frame having a 20 series of seats for the dies or die-holders.

In the accompanying drawings, Figure 1 is a plan view, partly in section, of my improved drawing-press. Fig. 2 is a side view of the same. Fig. 3 is a side view of a portion 25 of the mechanism on an enlarged scale. Fig. 4 is a transverse section on the line 4-4, Fig. 1; and Figs. 5 and 6 are transverse sections through the die-holder.

The pushing or reciprocating mechanism for 30 the mandrel or punch may be of any desired or preferred construction, that shown comprising a hydraulic or other power cylinder 1, in which works a suitable piston, the rod 2 of which is adapted to impart the required reciprocating motion to the mandrel or punch 3, the latter being hinged to the said piston-rod on a vertical pivot 4, so that the said mandrel or punch can be swung to one side, as shown in Fig. 1. The end of the power-cylinder 1 is suitably connected to the frame or standard 5, and the latter in turn is connected by means of the tie-rods 6 to a frame or standard 7 at the opposite end of the draw-bench, said tie-rods being supported at intervals, as required, by the standards or brackets 8, which are so constructed as not to interfere with the swinging of the mandrel or punch to one side. These tie-rods also serve as a support for the end of the piston-rod 2, 45 the latter being provided with rollers or other suitable guiding devices 9 and 10, which travel between the tie-rods 6. The die-holding frame 11 is connected to the frame 7 by means of the tie-rods 12 and is supported at its rear end in any suitable manner. By 50 means of the tie-rods 6 and 12 the die-holding frame 11 is tied firmly to the power-cylinder 1, so that displacement of the parts relatively to each other is impossible.

60 In order to swing the mandrel or punch 3 to the side, as shown in Fig. 1, I provide suitable reciprocating mechanism for engaging the said mandrel or punch and carry the same to one side in order to receive the cup-shaped 65 blank 13 and then to carry the mandrel or punch back into line with the drawing-dies in the frame 11. I have shown mechanism

suitable for this purpose, the same comprising a carriage 14, moving on a track 15 on the floor or foundation of the mill and to one 70 side of the draw-bench, and suitable mechanism for moving said carriage—such, for instance, as the reversing hydraulic or other power cylinder 16. The carriage 14 is provided with a suitable rest or support 17, on which the mandrel or punch is supported, and with suitable means for engaging said mandrel or punch, so that the latter is forced to move with said carriage, this means, as shown, comprising a block or "fork" 18, 80 hinged to the carriage in the lugs 19 and having the arms 20, which are adapted to receive the mandrel or punch between them. This block or fork is provided with a handle 22, by means of which it can be swung into the 85 vertical position (shown in Fig. 1 and in full lines in Figs. 2 and 3) to engage the mandrel or punch or dropped to the horizontal position, (shown in dotted lines in Fig. 2,) so as to be out of engagement with the said mandrel or punch. The carriage is provided with suitable wheels 23, which move on the tracks 15, said wheels being to the rear of the mandrel-support 17 and fork 18, this being necessary for the reason that the lower tie-rod 6 95 interferes with the inward movement of the carriage, and the latter must be so constructed that the portion carrying the mandrel-support and fork can be projected underneath the mandrel in the space between the 100 same and the lower tie-rod 6. For this reason the said carriage-body projects in front of the supporting-wheels 23, as shown. The operation of this part of the mechanism is as follows: When it is desired to place a cup-shaped blank 13 onto the mandrel or punch 3 preparatory to drawing the same in the dies in the frame 11, the carriage 14, with the block or fork 18 in its horizontal position, is moved forward to project said carriage underneath 110 the mandrel 3. The fork is then swung to its vertical position, so that the arm 20 thereof will engage the mandrel or punch, and the power-cylinder 16 is reversed to move the carriage outwardly, bearing with it the mandrel or punch, which rests on the seat or support 17, and carrying the same into the position shown in Fig. 1 to have the cup-shaped blank 13 slipped thereupon. The power-cylinder 16 is then again reversed, moving the carriage 120 inward and carrying the mandrel or punch into line with the dies in the frame 11, when the fork 18 is dropped to its horizontal position, so as to be disengaged from the mandrel or punch, and as soon as the latter has been 125 moved far enough forward by the pushing mechanism to engage its forward end with the die or as soon as the said mandrel or punch has been otherwise supported in line with the die—as, for instance, by means of a suitable support or frame which can be placed between the tie-rods 6—the power-cylinder 16 is again reversed and the carriage withdrawn 130 from underneath the punch and out of the

way of the pushing mechanism as it moves forward to force the blank through the dies. As soon as the mandrel or punch is again withdrawn the carriage is moved forward 5 underneath the same, the fork 18 swung to its vertical position to again engage the mandrel or punch, and the operation before described is repeated.

The die-holding frame 11 is provided with 10 a series of seats 25, whereby any desired number of dies 26 up to the number of seats in said frame can be placed in said frame, these dies either bearing directly against the seats 25 or being held in suitable holders 27, which 15 bear against said seats, as is the common practice in the art. To secure a proper and firm seating of the dies or die-holders on the seats 25 with their axes coinciding exactly with the axis of the punch, it is necessary 20 that they be accurately shaped. To facilitate this work, I construct the frame 11 of a series of blocks 28, each of which has its faces 29 and 30 parallel to each other, so that said faces can be readily machined, as by 25 means of an ordinary metal-planer. The faces 27 of the several blocks form the seats 25 for the dies 26 or die-holders 27. Each block is provided on its rear face with a recess 31, which is curved on its lower side, as 30 shown, and in which recess the die or die-holder rests. The stripper 32 is also placed in one of these recesses and rests either directly against the shoulders 33 or against a supplemental frame 34, placed in said recess. It is not necessary, however, to machine these recesses, as the dies will naturally 35 center themselves under the action of the mandrel or punch, it merely being necessary that the seats 25 be accurately formed in 40 order that the dies may be firmly supported and with their axes exactly coinciding with the axis of the mandrel or punch. It will be seen that as these seats are formed on the flat faces of the blocks 28 no difficulty in 45 properly machining the same will be experienced, and inasmuch as the two faces 24 and 30 of the blocks are parallel to each other they can be accurately machined down, so that when said blocks are secured together 50 all of the seats 25 will be exactly parallel with each other. These blocks are united

by any suitable means—such, for instance, as the tie-rods 12, passing through suitable holes formed in the blocks; but any other means suitable for this purpose can be employed. 55

What I claim as my invention, and desire to secure by Letters Patent, is—

1. In a drawing-press, the combination with a die and pushing mechanism, of a mandrel 60 or punch hinged to the pushing mechanism, means mounted for engagement with and disengagement from the mandrel or punch, and mechanism for moving the same transversely of the mandrel or punch. 65

2. In a drawing-press, the combination with a die and pushing mechanism, of a mandrel or punch hinged to the pushing mechanism, a carriage mounted to move transversely of the mandrel or punch, and means on the carriage 70 for engaging the mandrel or punch.

3. In a drawing-press, the combination with a die and pushing mechanism, of a mandrel or punch hinged to the pushing mechanism, reciprocating mechanism mounted to move 75 transversely of the mandrel or punch, and a "fork" hinged on the reciprocating mechanism and adapted to engage with or be disengaged from the mandrel or punch.

4. In a drawing-press, the combination with 80 a die and pushing mechanism, of a mandrel or punch hinged to the pushing mechanism, of a reciprocating carriage mounted at one side of the drawing-press to move transversely of the mandrel or punch and adapted to project underneath the same, and means on the carriage for supporting and engaging the mandrel or punch. 85

5. A die-holding frame comprising a series of blocks each provided with a die-seat on 90 one face thereof, and means for securing said blocks together.

6. A die-holding frame comprising a series of blocks each having parallel meeting faces and a die-recess in its rear face, and means 95 for securing said blocks together.

In testimony whereof I, the said PETER PATTERSON, have hereunto set my hand.
PETER PATTERSON.
